UNITED STATES PATENT OFFICE.

VICTOR M. SUMMA, OF ST. LOUIS, MISSOURI, ASSIGNOR TO AMERICAN CAR AND
FOUNDRY COMPANY, OF ST. LOUIS, MISSOURI, A CORPORATION OF NEW JERSEY.

CAR-UNDERFRAME.

1,022,710.

Specification of Letters Patent.

Patented Apr. 9, 1912.

Application filed June 2, 1911. Serial No. 630,928.

To all whom it may concern:

Be it known that I, VICTOR M. SUMMA, a citizen of the United States, residing at St. Louis, Missouri, have invented a certain new and useful Improvement in Car-Underframes, of which the following is a full, clear, and exact description, such as will enable others skilled in the art to which it appertains to make and use the same, reference being had to the accompanying drawings, forming part of this specification, in which—

Figure 1 is a half plan view of my improved car underframe; Fig. 2 is a vertical section taken approximately on line 2—2, Fig. 1; Fig. 3 is a transverse section taken approximately on line 3—3, Fig. 1; Fig. 4 is a transverse section taken approximately on line 4—4, Fig. 1; Fig. 5 is a plan view of the casting to which the ends of the truss rods are anchored; Fig. 6 is a transverse section taken on line 6—6, Fig. 5; Fig. 7 is a side elevational view of the casting seen in Fig. 5.

This invention relates to a new and useful improvement in underframes for railway rolling stock, the object being to sustain the major portion of the load by the center sill member and to transmit pulling 30 and buffing strains direct through such center sill member.

With this object in view, the invention consists in providing a casting at the bolster point for the anchorage of the ends of tension rods arranged substantially in the vertical plane of the center sill member and spaced apart therefrom, at the center of the car, by means of suitable struts.

In the drawings, 1 indicates the center sill member which is shown as a special rolled H-beam extending from bolster to bolster and preferably slightly beyond the bolster webs for the attachment of the draft sills 2, which latter are connected by means of suitable connection plates to the end sills 3.

4 are the bolster webs secured at their inner ends to the vertical legs of the H-beam center sill, said bolster webs having their bottom flanges connected to a bottom plate 5 and their top flanges to the top plate 6. Suitable side and center bearings are arranged in the bottom cover plate.

At points intermediate the bolsters are flanged transoms 7, whose inner ends are

connected to the vertical legs of the H-beam and whose outer ends are connected to the side sill members 8, which, in this instance, may be comparatively light, as the principal portion of the load is supported by the center sill. 9 is a casting whose top and bottom flanges are riveted or otherwise secured to the horizontal web of the H-beam and to the bottom bolster plate 5, said casting having a hollow boss 10 for the reception of the king pin and having vertically disposed depending flanges 11 extending inwardly from the bolster and secured to the inner faces of the vertical legs of the H-beam. This casting is also provided with perforated lugs 12 reinforced by suitable strengthening webs 70 between which are mounted truss rods 13, the eyes of said truss rods being held in position by a pintle rod 14. These truss rods 13 thus anchored at each end of the car, pass under struts or queen posts 15 75 which are secured between the legs of the H-beam and to the horizontal flange thereof. Suitable turn buckles 16 are arranged at appropriate points in the lengths of the rods for well known purposes.

My improved underframe is extremely simple in construction and comparatively light for the load designed to be carried. By its use, deep fishbellied center sills are avoided and the parts can be readily repaired when necessary.

I claim:

1. In a car underframe, the combination of bolster members and a trussed center sill construction in which the compression member is in the form of an H-beam to whose ends the tension members are anchored.

2. In a car underframe, the combination of bolster members and a trussed center sill construction comprising an H-beam compression member, struts, tension rods and castings interposed between the legs of the H-beam and secured to the horizontal web thereof.

3. In a car underframe, the combination of bolster members and a trussed center sill construction comprising an H-beam extending beyond the bolster points, draft sills connected to the vertical legs of said H-beam, anchoring members, and tension rods secured to said anchoring members.

4. In a car underframe, a trussed center sill in the form of an H-beam, struts inter-

posed between the legs of said beam, anchoring members also interposed between the legs of said beam, and tension rods.

5. In a car underframe, the combination of bolster members and a center sill construction for car underframes comprising an H-beam, castings secured to the horizontal web and vertical legs thereof at or near its ends, struts secured to said H-beam, and

tension rods coöperating with said struts 10 and anchored in said castings.

In testimony whereof I hereunto affix my signature in the presence of two witnesses, this 27th day of May, 1911.

VICTOR M. SUMMA.
